ELASTIC WHEEL FOR VEHICLES.

1,228,638.

Specification of Letters Patent.

Patented June 5, 1917.

Application filed May 7, 1914. Serial No. 837,034.

To all whom it may concern:

Be it known that we, MAURICE BAUDOU and RENÉ BAUDOU, of the French nationality, residing at Les Eglisottes, near Bordeaux, Gironde, in France, have invented 5 certain new and useful Improvements in Elastic Wheels for Vehicles, of which the following is a specification.

This invention relates to an elastic wheel 10 for railways, motor cars and other vehicles traveling on the ground, on roads or on rails.

This elastic wheel comprises three parts:

(1) A circumferential part constituted by 15 a metal rim with spokes of metal wires or of stamped out sheet metal. It is provided with the tread of metal or other material such as rubber.

(2) A central part secured to the hub or 20 to the axle, normally consisting of two equidistant metal disks. These two parts are distinct from each other.

(3) An intermediate part or vibrating ring arranged between the two preceding 25 parts and not in contact with the axle and rim. This part can slightly move in the radial direction between the two other parts, in accordance with unevenness of the ground or asperities of the road.

The vibrating frame consists of an annular metal disk provided with two concentric 30 series of holes to each of which is welded, for instance by autogenous welding, a metal tube projecting to an equal distance to the right and to the left of the disk. Into each of these tubes is driven with force an annular cylindrical core of compressed rubber having an outside diameter slightly larger than that of the tube. In the central 35 hollow portion of the core is mounted an ordinary spindle hub provided with ball bearings or rollers at each of its ends. The spindles of the spindle hubs of the smaller ring of cores pass through holes provided in 40 the parallel disks secured to the axle and constituting the central part, and are firmly secured to the said disks by means of nuts. The spindles of the hubs of the larger ring of cores pass through holes provided in two 45 parallel rings, for instance of angle irons secured to the circumferential part of the wheel and to its rim. Nuts screwed into the interior of the said rings, securely hold 50 in place the said hubs on the said rings.

The central disk is provided with two concentric series of tubes lined with rubber cores. It is arranged in a plane normal to the axle, and its metal tubes are arranged 55 parallel to the axle.

The reactions due to the difference in 60 level of the road, are elastically transmitted to the axle by the vibrating frame-work arranged between the circumferential part secured to the rim, and the central part secured to the axle.

The accompanying drawing shows this kind of elastic wheel.

Figures 1 and 2 show, in vertical section through the axis, the elastic wheel.

Fig. 3 is a separate view showing a side 70 elevation of the vibrating ring used in the construction of wheel shown in Fig. 1.

Fig. 4 is a separate view showing a side elevation of the vibrating ring used in the construction of wheel shown in Fig. 2. Fig. 75 5 is a section through the line X—X of Fig. 3 of a portion of the vibrating ring assumed to be hollow and represented on a larger scale.

The circumferential part comprises a 80 metal rim 1 having a tread band 2 thereon, and two parallel rings of angle iron 3 connected concentrically to the rim 1 by wires 4.

The central part is constituted by two parallel circular metal disks 5 mounted on 85 the axle A and held, if necessary, at an equal distance apart by distance rods.

The vibrating frame work consists in an annular metal disk 6 arranged between the rings 3 and the disks 5. In the holes drilled 90 in two concentric lines in the said disk 6, are rigidly secured by autogenous welding, metal tubes 7 into which are forced annular rubber cores 8 provided in their central hollow, with a spindle 9 supported by the core 8 by 95 means of ball bearings 10. The ends of the spindles 9 are secured, as regards the series of cores nearest to the axle A, to the disks 5 by means of nuts 11, while the ends of the spindles 9 of the series of cores 8 nearest to the rim 1, are secured to angle iron rings 3 by means of nuts 12. In order to prevent the cores 8 from coming out from the tubes 7, the extreme edges of the latter are expanded or flanged over against the ends of 100 the cores as shown. Any other method could be used for preventing them from coming out.

It will be seen that with this construction of elastic wheel, the intermediate part provided with tubes filled with rubber cores, being supported on the one hand by the axle 5 A and on the other hand by the rim 1, plays the part of vibrating frame work freely moving in the vertical plane under the impulses received by the wheel on contact with uneven portions of the road. It follows that 10 the shocks received by the tread band 2, are reduced before being transmitted to the concentric rings of rubber tubes, and that the axle receives these shocks only after they have been considerably softened.

15 It has been found that flexibility in the lateral direction is a drawback when the wheel is used for high speeds. In order to remove lateral flexibility, and give it a greater rigidity, cross-bars forming stops 14 and 15, are added.

20 On the radial lines going from the center of the disk 6 through the axes of the tubes 7, cross-bars 14 and 15 are rigidly secured to the disk 6, so as to project at each side of 25 the disk and touch the angle iron rings 3 and the disks 5 respectively (Figs. 1 and 3). These bars form stops which give a greater rigidity to the wheel.

25 The two ends of the spindles 9 passing through the axis of the tube 7 of the outer series, can also be secured to the ends 16 of a shackle or bracket 17 passing through the hollow hub of the disk 6 of the vibrating ring, and a cross-bar 15 can be rigidly secured to the disk 6 and to the arms 16 so as to project from the said arms and touch the disks 5 (Figs. 2 and 4). This arrangement of making the bars radial as at 16 also gives great rigidity to the wheel.

30 The ends of the cross-bars 15 can be rounded off in the shape of a ball (see Fig. 5). They are made of tempered steel in order that their sliding against the inner faces of the disks 5 should take place practically 35 without friction or wear. In order to lubricate the inner faces of the disks 5 against which strike the ends of the cross-bars 15 (Fig. 1), the vibrating ring 6 is hollow (see Fig. 5) and the cross bars are likewise hollow and perforated by holes 18 opposite to the hollow chamber 20 of the ring; the curved ends of the said hollow bars (Fig. 5) are likewise perforated in the center by a hole 19. As the chamber 20 is filled with oil, the 45 latter passes through the holes 18 in the bar 15 and flows through the holes 19 to the inner sides of the disks 5. Obviously the same arrangement may be used for lubricating the cross-bars 14 and the angle-irons 3.

50 We claim:

1. In an elastic wheel for vehicles traveling on roads or rails, the combination of a circumferential part comprising a rim and two concentric, parallel and circular rings connected to the rim by wires, a central part

formed by two parallel, metallic and circular rings mounted on the axle, and a vibrating ring formed by an annular, metallic disk placed in the middle of the plane of the wheel, between the parallel rings of the circumferential part and the parallel rings of the central part, the said vibrating ring being provided with two concentric rows of metallic tubes each inclosing an annular core of compressed rubber in the hollow hub of which is mounted a spindle combined with a ball bearing, the ends of the spindles of one of the rows of cores being secured to the rings of the central part and the spindles of the other row of cores being secured to the rings of the circumferential part, and two series of guides, the ends of one of them touching the inner faces of the circular rings. 70 75 80 85

2. In an elastic wheel for vehicles traveling on roads or rails, the combination of a circumferential part comprising a rim and two concentric, parallel and circular rings of angle iron connected to the rim by wires, a central part formed by two parallel, metallic and circular rings mounted on the axle, and a vibrating ring formed by an annular, metallic disk placed in the middle of the plane of the wheel, between the parallel rings of the circumferential part and the parallel rings of the central part, the said vibrating ring being provided with two concentric rows of metallic tubes each inclosing an annular core of compressed rubber in the hollow hub of which is mounted a spindle combined with a ball bearing, the ends of the spindles of one of the rows of cores being secured to the rings of the central part and the spindles of the other row of cores being secured to the rings of the circumferential part, and two series of guides, the ends of one of them touching the inner faces of the circular rings. 90 95 100 105 110

3. In an elastic wheel for vehicles traveling on roads or rails, the combination of a circumferential part comprising a rim and two concentric, parallel and circular rings of angle iron connected to the rim by wires, a central part formed by two parallel, metallic and circular rings mounted on the axle, and a vibrating ring formed by an annular, metallic, hollow disk placed in the middle plane of the wheel, between the parallel rings of the circumferential part and the parallel rings of the central part, the said vibrating ring being provided with two concentric rows of metallic tubes each inclosing an annular core of compressed rubber in the hollow hub of which is mounted a spindle combined with a ball bearing; the ends of the spindles of one of the rows of cores being 115 120 125 130

secured to the rings of the central part and the spindles of the other row of cores being secured to the rings of the circumferential part, and two concentric rows of hollow 5 cross-bars rigidly secured to the middle disk and projecting to the same extent at each side of the disk so that the ends of the outer row of bars touch the inner faces of the angle iron rings, and the ends of the inner

row of bars touch the inner faces of the parallel rings of the central part, the bars being provided with small holes so that lubricant placed in the hollow disk can pass out from the ends of the bars.

In testimony whereof we have signed our 10 names to this specification.

MAURICE BAUDOU.
RENÉ BAUDOU.
